UNITED STATES PATENT OFFICE.

JOHN GILMOUR, OF OWENSBORO, KENTUCKY.

CASK.

No. 866,014.

Specification of Letters Patent.

Patented Sept. 17, 1907.

Application filed August 21, 1906. Serial No. 331,515.

To all whom it may concern:

Be it known that I, JOHN GILMOUR, a citizen of the United States, and a resident of Owensboro, in the county of Daviess and State of Kentucky, have made 5 a certain new and useful Invention in Casks; and I declare the following to be a full, clear, and exact description of the same, such as will enable others skilled in the art to which it appertains to make and use the invention, reference being had to the accompanying 10 drawings, and to letters or figures of reference marked thereon, which form a part of this specification.

Figure 1 is a side view of the invention as applied. Fig. 2 is a section on the line 2—2, Fig. 3. Fig. 3 is a section on the line 3—3, Fig. 1. Fig. 4 is a section on 15 the line 4—4, Fig. 1. Fig. 5 is a detail view of one of the lining straps.

The invention has relation to knock down hogsheads for leaf tobacco, and other purposes, and it consists in the novel construction and combinations of devices as 20 hereinafter set forth.

The object of the invention is mainly to provide a receptacle of the character indicated, wherein the inside wall is sheer and without obstruction, and whose staves are adapted to be put in form and held together 25 by simple means readily applied, and readily disconnected. Other objects and advantages will hereinafter appear.

In the accompanying drawings illustrating the invention, the letter *a*, designates wooden staves, which 30 are designed to be smooth throughout on their inside and outside surfaces and beveled on the edges in accordance with the curvature of the hogshead. Some of these staves are provided with perforations *b*, near their ends. At each end of the hogshead are the heads 35 *c*, and *d*, which may be made in sections. A croze or groove in the staves for engagement with the head is not required.

The staves are set up and held in position by means 40 of wire bulge hoops *e*, having loop ends *f*, and wire connections *g*. These wire hoops are adjustable and are designed to be drawn tightly around the set up staves by means of a drawing clamp (not shown) which holds the loop ends in position for the attachment of the link or connection *g*.

45 The staves are secured at their ends by means of external end hoops *k*, which are provided with slots *m*, at intervals of six or nine inches, these slots being designed for the passage of short bolts *n*, which are secured by nuts. The slots are designed to be long 50 enough to allow for some irregularity in the position of the holes *b*, of the staves, through which the bolts also pass.

55 Sectional flange stops or lining straps *p*, are designed to be placed inside the ends of the staves on the outside of the heads, these inside stops being curved nearly in accordance with the contour of the hogshead inside the

staves, but having some outward spring so as to provide for slight differences in the size of the staves. The lining stops are therefore of strap like form, and have slight flanges *t*, on their inside edges, designed to abut 60 against the head sections. Slots *m*, are also provided in these strap stops at intervals apart similar to those of the outer bands. The lining straps are short, being less than semi-circular, as they are not required to abut 65 against each other at their ends, because of the greater facility of adjustment. As these sectional straps are outside the head, it is apparent that within the packing space of the hogshead there is no obstruction, the heads being prevented from falling in by the automatic pressure of the compressed tobacco within the 70 hogshead.

In setting up the barrel, the staves are set up within a form, and the wire hoops are placed around them at the bulge, near each end. These wire hoops are drawn tightly, causing the staves to close laterally together, 75 and the link connections being secured to the loops of the straps, the staves will be held together in shape and the form may be removed. Each link connection consists of a short piece of stout wire having a loop or hook *s*, at one end, and a pliable hook portion *w*, at the 80 other end.

When the loops of the wire hoop are drawn to position, the link being connected to one loop of said hoop, is adjustably secured to the other hoop by means of a pair of pincers. In setting the staves in position, those 85 which have perforations are placed alternately with the imperforate staves, so as to have their holes in proper position for the connection bolts. Or, each stave may be provided with perforations.

The outside end hoops *k*, are then forced on the ends 90 of the staves, and the stop straps for the bottom head are put in place. Then the bottom head is forced in position against the flanges of the stop straps. The connection bolts pass through the sectional stop straps, the staves, and the external hoop, and are secured by 95 the nuts of such bolts.

The hogshead is now ready for filling, and the tobacco is forced in by means of a hydraulic or other press. The sections of the top head having been placed in position next to the tobacco, this head is also 100 forced to position within the circle of stave ends, and while held therein by the press plunger, the strap stops for this head are put in place and secured by their connection bolts. The expansive pressure of the tobacco holds the heads against the flanged stop straps, 105 and these being held securely by the bolts, which connect them to the staves and the external hoops, the hogshead is secure.

When the hogshead is to be discharged, the bolts are withdrawn, the wire hoops disconnected, by releasing 110 their end connections, and the external band hoops are knocked off. The staves then fall away from the

tobacco. As no part of the hogshead is injured, it is apparent that it can be packed in small compass with its connecting hoops and other parts, and reshipped to the place from whence it came for repacking.

5 Having thus described my invention, what I claim as new and desire to secure by Letters Patent is:

A knock down cask, consisting of a series of staves having a smooth inner surface throughout, and end perforations, external detachable end hoops, having slots, internal 10 elastic arcuate lining straps having slots corresponding to the slots of the end hoops and inner flanges, connection

bolts passing through the stave perforations and the slots of the end hoops and lining straps, detachable heads, abutting against the inner flanges of the lining straps, and detachable wire bulge hoops having a separable wire connection. 15

In testimony whereof I affix my signature, in presence of two witnesses.

JOHN GILMOUR.
